Primary Examiner — Robert M Spear*Assistant Examiner* — Marissa J Cash(74) *Attorney, Agent, or Firm* — Edward L. White(57) **CLAIM**

The ornamental design for a sealing cap, as shown and described.

DESCRIPTION

FIG. 1 is a side view thereof.

FIG. 2 is a top view of a sealing cap.

FIG. 3 is a bottom view thereof; and,

FIG. 4 is a perspective view thereof.

The broken line in FIG. 3 illustrates the innermost position looking from above where the material stops and forming, no part of the claim.

1 Claim, 2 Drawing Sheets(56)
